UNITED STATES PATENT OFFICE.

JAMES C. BROWNING, OF SALTPOINT, NEW YORK.

MANIFOLD-COPY BOOK.

SPECIFICATION forming part of Letters Patent No. 708,810, dated September 2, 1902.

Application filed March 28, 1902. Serial No. 100,498. (No model.)

To all whom it may concern:

Be it known that I, JAMES C. BROWNING, a citizen of the United States, residing at Salt-point, in the county of Dutchess and State 5 of New York, have invented certain new and useful Improvements in Manifold-Copying Books, of which the following is a full and complete specification, such as will enable those skilled in the art to which it appertains 10 to make and use the same.

The object of this invention is to provide an improved manifold-copying book for use by clerks, salesmen, and others desiring to make two or more copies of an entry, sale, or other 15 transaction; and with this and other objects in view the invention consists in a manifold-copying book constructed as hereinafter described and claimed.

The invention is fully disclosed in the following specification, of which the accompanying drawings form a part, in which the separate parts of my improvement are designated by the same reference characters in each of the views, and in which—

25 Figure 1 is a plan view of my improved manifold-copying book with one side of the back and fly-leaf at the opposite side turned backwardly as when the copying-book is in use; Fig. 2, a side view thereof; Fig. 3, a section on the line 3 3 of Fig. 1; Fig. 4, a view similar to Fig. 1, showing a modification; Fig. 5, a side view thereof; Fig. 6, a partial plan view; and Fig. 7, a view similar to Fig. 6, showing a detail of the construction.

35 In the drawings forming part of this specification, I have shown a back or cover of the usual form and comprising two parts a and a^2 , connected centrally by a flexible portion a^3 . I have also shown a pad which is designed by the reference character b and which is composed of a plurality of leaves connected at one end, as shown at b^2 , and said pad is provided with a fly b^3 , adapted to enter a pocket b^4 of the part a of the cover and by 45 which the pad is held in place, and the said pad is provided opposite the fly b^3 with a fly-leaf b^5 , all these parts being of the usual construction and forming no part of this invention.

50 In the practice of my invention I secure transversely of the free end of the part a of

the back or cover a carbon-sheet and a plate-holder c , which is plaited or folded in bellows form, as clearly shown in Fig. 2, and which is provided with a transverse strip or flange 55 c^2 , which constitutes an attachment for a carbon-sheet d and a writing plate or sheet e , the latter being composed of stiff paper, cardboard, celluloid, or any other suitable material. In practice the writing sheet or plate e 60 and the carbon-sheet d , which is placed thereon, are connected with a strip or flange c^2 by hooks f , which are connected underneath said strip or flange by a spiral spring g , as clearly shown in Fig. 3, and in the operation of using 65 the pad or making one or more copies of the entry, sale, or other record one of the sheets of the pad b is placed on the sheet or plate e , the carbon-sheet d is placed thereover, and another leaf or sheet of the pad is placed over 70 said carbon-sheet. It will be understood that a number of copies of any entry or record may thus be made, all that is necessary being to increase the number of carbon-sheets d or to use two or more of said carbon-sheets. 75

By making the carbon-sheet and plate-holder as shown at c I adapt the holder to pads of different thicknesses, it being understood that said holder may be adjusted so as to adapt itself to very thin or very thick pads, 80 and the writing plate or sheet e and the carbon sheet or sheets d may in the form of construction shown be detached whenever desired by detaching the hooks f , and new carbon-sheets may thus be substituted whenever 85 necessary. The writing plate or sheet e may, however, be permanently connected with the flange or strip c^2 of the holder or may be formed integrally therewith, if desired, without departing from the spirit of my invention 90 or sacrificing its advantages, and in Figs. 4 to 7, inclusive, I have shown a construction which admits of this operation. In this form of construction the transverse strip c^2 of the carbon-sheet and plate-holder c is provided 95 with a transverse slot or opening h , and the writing-plate e is secured to said transverse strip or may form a continuation thereof, and a supplemental transverse strip h^2 of comparatively stiff material is provided to which the 100 carbon-sheet d is secured in any desired manner, and the strip h^2 is slotted at its opposite

- ends, as shown at h^3 , so as to form projecting tongues h^4 , which are folded over along the dotted lines h^5 , and the body portion h^6 of said strip, including the tongues h^4 when so folded, 5 is passed through the slot h , and said tongues h^4 are extended outwardly and the edge portion h^6 bent flat with and against the bottom of the transverse strip c^2 , and this securely holds the carbon-sheet in place, and it will be 10 apparent that a plurality of carbon-sheets may be connected with the strip h^2 , if desired.
- Having fully described my invention, what I claim as new, and desire to secure by Letters Patent, is—
- 15 1. A manifold-copying book provided with a pad one side of the back being provided transversely at the free ends of the leaves of the pad with a plaited or folded carbon-holder provided at its free edge with a flange or strip 20 and spring-connected hooks engaging the ends of said flange or strip and adapted to

hold a carbon-sheet, substantially as shown and described.

2. A manifold-copying book comprising a pad and the usual back or cover, one side of 25 the back or cover being provided at the end thereof adjacent to the free ends of the leaves of the pad with a transversely-plaited holder which is connected therewith at one edge, and the other or free edge of which is provided 30 with a transverse member, and means for connecting a writing sheet or plate and a carbon-sheet with said member, substantially as shown and described.

In testimony that I claim the foregoing as 35 my invention I have signed my name, in presence of the subscribing witnesses, this 20th day of March, 1902.

JAMES C. BROWNING.
